No. 611,431.

Patented Sept. 27, 1898.

C. M. HOLCOMB.

PLUNGER FOR PAPER BOX MACHINES.

(Application filed July 30, 1897.)

(No Model.)

UNITED STATES PATENT OFFICE.

CHARLES M. HOLCOMB, OF NEW YORK, N. Y., ASSIGNOR TO ALFRED BIRNIE,
OF SPRINGFIELD, MASSACHUSETTS.

PLUNGER FOR PAPER-BOX MACHINES.

SPECIFICATION forming part of Letters Patent No. 611,431, dated September 27, 1898.

Application filed July 30, 1897. Serial No. 646,484. (No model.)

To all whom it may concern:

Be it known that I, CHARLES M. HOLCOMB, a citizen of the United States, and a resident of New York, (Brooklyn,) in the county of 5 Kings and State of New York, have invented certain new and useful Improvements in Extensible and Contractible Former-Plungers for Paper-Box Machines, of which the following is a specification.

10 This invention relates to improvements in folding, forming, or creasing plungers for machinery for making paper boxes, envelopes, &c., but more particularly paper boxes, and especially pertains to folding-plungers which 15 are adjustable as to size, so that a single plunger may be employed for the production of paper boxes of varying lengths and widths within a given reasonable range.

The invention consists in a folding-plunger 20 comprising parts and arrangements all substantially as will hereinafter fully appear, and be set forth in the claims.

Reference is to be had to the accompanying drawings, in which—

25 Figure 1 is a plan view of the improved adjustable plunger. Fig. 2 is in part a side view and in part a vertical sectional view of the plunger as taken on the line 2 2, Fig. 1. Fig. 3 is an end view of the plunger. Fig. 4 is a 30 cross-sectional view of the plunger as taken vertically on the planes indicated by the line 4 4, Fig. 1. Fig. 5 is a partial end view of the plunger, showing a supplemental equipment therefor, hereinafter described.

35 Similar characters of reference indicate corresponding parts in all of the views.

The sectional, extensible, and contractible plunger comprises four blocks or sections A A, each having bottom 10, end face 12, and side 40 face 13, squared to each other and arranged and held with their bottoms 10 all in a common horizontal plane and their side and end faces coincident with and common to the planes corresponding to the sides of a true 45 rectangle, the blocks being separated crosswise and endwise from each other and firmly held in such separation by the means to be described, so that for the time being to all intents and purposes the plunger when in use 50 is as efficient and stable as if constructed solid and non-adjustable.

Each of the blocks A is provided at its upper and lower portions with the angular extension 14, inwardly longitudinally extending, and the blocks about centrally of these 55 extensions 14 are drilled and tapped, as indicated in Figs. 1 and 2, and receive the screw engagement therein of the threads of the screw-shafts B, which are right and left hand threads, so that the turning of the shaft in 60 one direction will cause the end blocks to be distended, while the turning of the shaft in the other direction will insure their assuming approached relations. As here shown for each and both of the side pairs of the blocks or sections A A there are two of these screw-shafts B, arranged longitudinally in parallelism and entering the screw-sockets in the upper and lower portions of both of the blocks at one 65 side of the plunger. 70

Each screw-shaft B has integrally formed at its middle the gear-wheel C with the hubs a a at its opposite faces, and an opposing pair of flat plates b b, having circular apertures 16, are fitted about and supported upon the 75 said hubs a a and in turn serve to support the hubs or gudgeons of the intermediate gear-wheels d d.

One of the gudgeons or journal-hubs for the intermediate gear-wheels d has thereon a 80 projection d², of polygonal form, which is also perforated, whereby it may be either turned by a wrench or a spanner or suitably otherwise, so as to impart simultaneously a rotation to both of the double or right and left 85 hand screws, which engage in upper and lower threaded sockets to be moved strictly horizontal toward and from each other and preventing any tendency of the one to be canted in such a way that its end 12 would not be 90 perpendicular.

jj represent lock-nuts screwing on the screw-shafts and setting up against the inner ends of the sections A.

A bar or dowel D is provided for each of 95 the blocks A at one side of the plunger, the same projecting horizontally crosswise and entering a socket 17 therefor in the correspondingly-opposing block.

The sockets 17 17 in the opposing pairs of 100 the blocks exactly match, so that whatever may be the distention or contraction of one side

pair of the plunger-blocks A A the opposing pair of blocks may readily be brought to have exactly the same distention or contraction by reason of the engagement of the dowels in the 5 sockets therefor in all of the four blocks. The opposite side pair of blocks may be adjusted crosswise relative to each other by sliding them on the dowels, the set-screws *f* having been loosened preparatory to effecting the 10 adjustment and tightened up again to connect the blocks firmly with the dowels after the lateral adjustment has been accomplished. The dowels also insure that the blocks A A at one side must stand exactly parallel with 15 the pair of blocks at the other side of the plunger.

In effecting the adjustment of the plunger longitudinally the dowel between one end pair of the blocks is removed. The adjustment of 20 one side pair of the blocks is effected by operating the right and left hand screw for said side pair. Then the right and left hand screw for the other side pair of the blocks is operated, so that these blocks are opposite those 25 of the first adjusted side pair, and the dowel is replaced and secured by the set-screws therefor. Of course in effecting the transverse adjustments one set-screw for each of the dowels must be loosened.

30 This plunger is supported on the plunger-shaft F by the horizontal bar G, which ranges over the sectional plunger diagonally, substantially as shown in Fig. 1, the opposite end portions of this bar having the slots *g*, through 35 which the confining-bolts *h* are passed, their screw-shanks entering the tops of the diagonally-opposing blocks A A, while their heads have a clamping bind upon the top of the bar G. When the plunger is to be adjusted, these 40 confining-bolts are loosened, whereupon both longitudinal and transverse adjustments may be accomplished without interference by the bar.

The plunger herein described is especially 45 available in paper-box machines of the description shown and described in Letters Patent of the United States, dated May 28, 1894, No. 519,531, wherein the most forcible setting pressure is brought against the ends of the 50 folder and former plunger, and it will be observed that this pressure is ably resisted by the threads of the screw-shafts B, which receive the end thrust imparted against the ends of the blocks or sections A A.

55 Inasmuch as it is desired to so construct the plunger that the opposite side pairs of blocks may be for narrow boxes brought close together, it will be observed that the gears on and between the pairs of right and left 60 hand-threaded screw-shafts and the supports *b b* for the intermediate ones of these gears occupy a width no greater than the thickness transversely of the blocks, as will be especially apparent on reference to Figs. 65 1 and 4, and because it is desirable to acquire the most even and uniform operation by the upper and lower pairs of screws-shafts

in relation to each of the side pairs of the plunger-blocks, so that a considerable distance between the shafts is required, it becomes desirable to use more than one intermediate gear between the upper and lower shaft-gears, so as to secure a sufficiently long train to reach from the one shaft to the other, and yet not to occupy the excessive width. 75 As shown, to correspond with the gearing which assures that the upper screws will be caused to rotate in a reversed direction from the lower screws the upper right and left hand screws B B are arranged with their 80 threads reversed from the threads of the lower screws, so that both screws will operate to move the upper and lower portions of each block at one time in the same direction.

Inasmuch as this plunger may be utilized 85 in paper-box or analogous machines in which the pressure against the blank and end of the plunger is somewhat within the corner adjoining the lateral side of the plunger, I find it occasionally advantageous to provide 90 a removable and adjustable plate M, which traverses the distance between the end pair of sections A, which is detachably confined by the set-screws *n*, which are passed through the countersunk slots *m* in the plate and 95 into the sections A.

Having thus described my invention, what I claim, and desire to secure by Letters Patent, is—

1. An extensible and contractible former- 100 plunger consisting of four blocks or sections, the front and rear side pairs being respectively screw-engaged by right and left hand screw-shafts, the blocks at one side having transversely-extending dowels which play 105 through sockets therefor which are provided in the opposing pair of said blocks, and set-screws for confining said blocks and dowels.

2. An extensible and contractible folder- 110 plunger comprising four blocks or sections arranged at the corners of a rectangle, means whereby the opposite end pairs are supported and adjustably confined in suitably approached or distended relation, means where- 115 by the opposite side pairs of the blocks are supported and adjustably confined in approached or distended relations, the plunger-shaft having the bar G, the ends of which are longitudinally slotted and which ranges 120 over and between diagonally-opposing pairs of said blocks and the headed bolts *h h* adjustably confining said bar G upon said diagonally opposite blocks, substantially as de- 125 scribed.

3. An extensible and contractible folder- 130 plunger comprising opposite end sections, upper and lower pairs of right and left hand screw-shafts engaging said sections, means for turning one of said screw-shafts and means 135 whereby, from the rotation thereof, the other of said shafts will be also turned, for the purpose set forth.

4. An extensible and contractible folder-

plunger comprising four sections arranged at the corners of a rectangle, the opposite side pairs thereof having combined therewith screw-shafts in pairs, the turning of which draw or distend the said screw-united side pairs of the sections, means whereby one side pair of the sections is adjustably guided transversely relative to and connected with the other side pair, and means whereby, from the rotation of the one screw-shaft of each side pair of the sections, the other screw-shaft for said side pair will also be rotated, for the purposes set forth.

5. An extensible and contractible folder-plunger comprising opposite end sections, upper and lower pairs of right and left hand screw-shafts, screw engaging said sections, each having at its middle a gear-wheel, supports mounted on said screw-shafts adjacent the gear-wheels and supporting intermediate gearing and means for turning one of the gears, for the purpose set forth.

6. An extensible and contractible folder-plunger comprising opposite end sections, upper and lower pairs of right and left hand screw-shafts engaging said sections both having gear-wheels at their middle portions the plate *b* having perforations, whereby it engages for its support, the portions of the screw-shafts adjacent the gear-wheel, and having mounted thereon the intermediate gear-wheels *d*, one of said intermediate gear-wheels having the projection *d*² whereby to

turn it, substantially as and for the purposes set forth.

7. In a contractible and extensible former-plunger in combination, the four blocks or sections *A A* having the longitudinal screw-sockets in pairs, the transverse horizontal sockets *17*, and the dowels *D* engaging therein, the set-screws *f* for said dowels, the upper and lower pairs of right and left hand screw-shafts for each side pair of said blocks which screw-engage in said threaded sockets therefor and which shafts have at their middle 45 portions the gear-wheels *C C* and the hubs *a*, the plates *b* which are apertured and supported upon said hubs *a* and on which are supported the intermediate gear-wheels *d d*, the lock-nuts *j j* on said screw-shaft adapted 50 to be set against the inner end faces of the said blocks, the plunger-shaft *F* having the bar *G* horizontally ranging between and over the diagonally opposite pairs of the blocks and having their ends longitudinally slotted, 55 and the headed bolts *h h* adjustably confining said blocks to said bar, substantially as described.

In testimony that I claim the foregoing as my invention I have signed my name, in presence of two witnesses, this 13th day of July, 1897.

CHARLES M. HOLCOMB.
